UNITED STATES PATENT OFFICE

159,038

VENDING MACHINE

Hal Bergstrom, New Rochelle, N. Y., assignor to American Chicle Company, Long Island City,
N. Y.

Application September 28, 1949, Serial No. 5,202

Term of patent 14 years

(Cl. D52—3)

To all whom it may concern:

Be it known that I, Hal Bergstrom, a citizen of the United States, residing in New Rochelle, county of Westchester, State of New York, have invented a new, original, and ornamental Design for a Vending Machine, of which the following is a specification, reference being had to the accompanying drawing, forming part thereof.

I claim:

The ornamental design for a vending machine, substantially as shown.

HAL BERGSTROM.
